UNITED STATES PATENT OFFICE.

WILLIAM JOHN LANDIN, OF ST. PAUL, MINNESOTA.

HAIR-PIN.

1,247,414.

Specification of Letters Patent. Patented Nov. 20, 1917.

Application filed April 12, 1917. Serial No. 161,455.

To all whom it may concern:

Be it known that I, WILLIAM JOHN LANDIN, a citizen of the United States, residing at St. Paul, in the county of Ramsey, 5 State of Minnesota, have invented a new and useful Hair-Pin, and I do hereby declare the following to be a full, clear, and exact description of the invention, such as will enable others skilled in the art to which it applies to make and use the same.

The present invention relates to certain new and useful improvements in hairpins, and has for its object to provide a device of this character which embodies novel features of construction whereby coöperating spring jaws are provided at the head of the hairpin for engagement with stray locks or the like, thereby enabling a stray lock to be secured and held in proper position without difficulty.

Further objects of the invention are to provide a hairpin of this kind which is comparatively simple and inexpensive in its construction, which can be easily handled and manipulated in substantially the same manner as an ordinary hairpin, which can be caused to engage several stray locks of hair, and which will be practically invisible when placed in position.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of a hairpin constructed in accordance with the invention.

Fig. 2 is a perspective view of one of the hairpins, the various spring jaws being shown as sprung into an open position for the purpose of illustrating more clearly the manner of bending the wire.

Fig. 3 is a sectional view on the line 3—3 of Fig. 1.

Corresponding and like parts are referred to in the following description and indicated in all the views of the drawings by the same reference characters.

The hairpin is designed to be formed from a single length of spring wire, and includes the two arms 1 which are designed to be inserted into the hair in the usual manner, and

may be waved at 2 so as to engage and interlock with the strands of the hair to prevent accidental loss of the hairpin. At the head of the hair pin the arms 1 are bent laterally 65 in opposite directions, as indicated at 3, and then doubled back and forth to provide a pair of opposed side loops A at one side of the head, and opposed top and bottom loops B at the opposite side of the head, the loops 65 A and B being arranged in an angular relation to each other, and projecting laterally in opposite directions from the head of the hair pin. The free ends of the side loops A are flared apart at 4 to provide a mouth leading 70 into the space between the jaws. In a similar manner the free ends of the upper and lower jaws B are flared apart at 5, these flared mouths enabling a stray lock of hair or any other object which it may be desired 75 to secure in position to be easily drawn between the jaws so as to be gripped thereby.

By reference to Fig. 2 it will be observed that in doubling the wire back and forth to form the opposed resilient looped jaws A 80 and B, a series of strands 6 are provided, said strands extending transversely the full width of the head of the hairpin and normally fitting closely together. The two upper strands 6 at the head of the hairpin form the 85 sides of the upper looped jaw B and one side of each of the side jaws A. The third and lower strand 6 forms the other side of one of the side jaws A and one side of the lower jaws B, the other side of the said 90 lower jaw B being formed by the laterally bent end of one of the main arms 1, while the laterally bent end of the other main arm 1 forms the lower side of the other side jaw A. A number of stray locks or the 95 like can be readily inserted between the jaws so as to be firmly gripped thereby, and the hairpin then inserted in position in such a manner as to be invisible itself and hold the stray locks in place.

Having thus described the invention, what I claim as new and desire to secure by Letters Patent, is:—

1. A hairpin formed of wire and including side arms connected by a head which is 105 doubled back and forth transversely to provide opposed sets of looped jaws adapted to be used in engaging stray locks of hair.

2. A hairpin formed of wire and including side arms having the ends thereof at the 110 head of the hairpin bent laterally in opposite directions and doubled back and forth

to provide a pair of opposed resilient looped jaws at each side of the hairpin, said jaws being adapted to be used in gripping stray locks of hair.

5 3. A hairpin formed of wire and including side arms having the ends thereof at the head of the hairpin bent laterally in opposite directions and doubled back and forth to provide opposed looped side jaws at one 10 side of the head and opposed looped upper and lower jaws at the opposite side of the head, the two sets of jaws being arranged in an angular relation to each other and being adapted to be used in gripping stray locks of

15 hair.

4. A hairpin formed of wire and including side arms having the ends thereof at the

head of the hairpin bent laterally in oppo-

site directions and doubled back and forth to provide three transverse strands, the 20 main strands and laterally bent ends of the main arms being connected at one side of the head by opposed side loops, and at the opposite side of the head by opposed upper and lower loops arranged in an angular relation 25 to the side loops, the opposed loops providing spring jaws adapted to be used in gripping stray locks of hair.

In testimony whereof I have signed my name to this specification in the presence of 30 two subscribing witnesses.

WILLIAM JOHN LANDIN.
